UNITED STATES PATENT OFFICE

2,626,091

PORTABLE GARMENT SUPPORTING AND
STRETCHING DEVICE

Aristide Reguitti, Agnosine Brescia, Italy

Application October 14, 1949, Serial No. 121,259
In Italy March 30, 1949

1 Claim. (Cl. 223—61)

1

This invention relates to portable garment supporting devices and more particularly to garment supporting and trouser stretching devices.

It is one of the objects of the present invention to provide a compact, useful and easily operable garment supporting device which may be placed within a room, since it takes up only relatively little space and is adapted to receive and hold a variety of articles of wearing apparel and accessories.

The invention is hereinafter explained in greater detail and with reference to the attached drawing in which one embodiment of the invention is shown.

Fig. 1 is a front elevational view of the device made in accordance with this invention.

Fig. 2 is a sectional view taken along lines 2—2 of Fig. 1.

Fig. 3 is a detailed view partly in section and taken along lines 3—3 of Fig. 2.

Fig. 4 is a longitudinal section and drawn to an enlarged scale showing various positions of the device seen in Fig. 1.

Referring now more particularly to the drawing there is shown in Fig. 1 a garment supporting and trouser stretching device having upright supports or standards 1 which are interconnected to each other at their base members 2, the latter being preferably provided with casters 3 in order to facilitate displacement of the device. Supports 1 are further connected by transverse members 4 and 5 extending in the respective upper and central portions of the device and further by transverse members 6 extending into the base members 2. These transverse bars 6 are provided with metallic ledges 7 for the purpose of supporting the shoes of a person placed on said transverse members 6.

Intermediate the upper ends of the upright supports 1 there is fitted a recessed member 8 forming a tray which is adapted to receive accessories for wearing apparel, etc., and is further adapted to brace the upper ends of upright supports or standards 1. Connected to this tray rearwardly thereof is a coat hanger 9 which is sufficiently spaced from the upright standards 1 to avoid any crushing of a coat when suspended from garment hanger 9. Between transverse members 4 and 5 connecting the upright standards or supports 1 with each other there extend stationary plates 10 which carry between them and said upright supports 1 sidewardly extending studs 11.

In the lower part of the side or upright supports there are disposed spindles 12 on opposite

2

sides of which are pivotally supported the bearing pieces 13 and 14 with an adjacent end 15 from which extend the ends of coil springs 16 which surround the spindles 12 (see Fig. 3).

Clamping plates 17 and 19 extend between these bearing pieces 13, 14 and are, respectively, connected thereto. Between bearing pieces 13 extends movable transverse clamp plate 17 which, on account of the spring pressure obtained through springs 16, has the tendency to normally assume an inclined forward position with respect to clamp plate 19 as shown in Fig. 4 in which stop pins 18 connected to standards 1 are disposed to abut against said clamp plate 17, to prevent further forward movement of plate 17 against plate 19.

With bearing pieces 14 is connected the aforesaid transverse plate 19 which carries the vertical and swingable plates 20 which in turn terminate in transverse bar 21. Plates 17 and 19 form clamping means for receiving one end of a pair of trousers as will be later explained. Stop members 22 are fixed at the inner face of the upright supports 1 to limit the swinging movement of the clamping plate assembly 19—20—21 as is evident from Fig. 4 (shown in full lines).

On the vertical movable plates 20 are, respectively, pivotally affixed the coupling levers 23 provided with hooks 24 whereby the vertical plates 20 may be coupled to abut against plates 10 by the engagement of the hooks 24 of levers 23 with the side studs 11.

The automatic trouser stretcher device according to the invention is operated in the following manner:

The vertical plates 20 together with transverse members 19 and 21 are first disengaged from fixed plates 10 and are brought to open position (designated by I in Fig. 4) so that the trouser stretcher is in fully open position.

After the trousers have been placed in position on plate 20 so as to extend over the transverse member 21, it will be apparent that clamp means 19 first approaches during its swinging movement about spindles 12 and toward clamp means 17 said movable transverse clamp means 17 in such manner that assembly 19—20—21 assumes another or median position (position II in Fig. 4). In this position and due to the force of the springs 16 on bearings 13 and 14 clamping plates or means 19 and 17 will be pressed together so that the parts of the trousers placed therebetween will be held and clamped in compressed condition.

Subsequently thereto a further rotary motion is performed about spindles 12 whereby the assem-

bly 19—20—21 together with plate 17 assumes a closed position (as indicated by III in Fig. 4) whereby the hooks 24 engage the studs 11, while the trousers are held between the now arranged vertical plate members 10 and 20 and are automatically pressed owing to the pressure of these plate members against each other.

It will be seen from the aforesaid disclosure that due to the rotative movement of the clamping plates 17 and 19 with respect to each other and relatively to the stationary upright plates 10 about the pivot pins or spindles 12 stretching of the trousers and subsequent pressure on the trousers will be brought about.

While a preferred embodiment of the invention has been shown and herein described, it will be understood that the same is capable of modification without departure from the general scope and spirit of the invention as defined in the claim.

Having thus described the invention, what is claimed as new and desired to be secured by Letters Patent, is:

A portable garment supporting and stretching device comprising, in combination, two spaced-apart upright standards having a supporting base therefor, said standards terminating in lower and upper ends, a recessed member connecting said upper ends with each other for bracing said standards, aligned spindles extending toward each other and mounted on said standards adjacent the lower ends thereof, spaced stationary plate members extending between and fixed to said standards, first movable clamp means extending below said stationary plate members and between said standards and springedly supported on said spindles for swinging movement forwardly of said

stationary plate members, second movable clamp means springedly supported on said spindles and for swinging movement relative to said first clamp means, whereby both said clamp means are normally held in spaced relation to each other and project beyond said stationary plate members, movable plate members spaced from each other and connected with said second clamp means for movement with the latter, whereby a garment placed over said second plate members and in contact with said second clamp means may first be moved to abut against said first clamp means, to thereby facilitate stretching of the garment along said movable plate members, said garment being subsequently movable toward said stationary plate members for pressing purpose between the latter members and said movable plate members, and coupling means for releasably maintaining said movable plate members together with said second clamp means against said stationary plate members, while said first clamp means is substantially in alignment with said stationary plate members.
